(57) **CLAIM**

The ornamental design for refrigerator filter, as shown and described.

DESCRIPTION

FIG. 1 is a front view of a refrigerator filter showing my new design;
FIG. 2 is a rear view thereof;
FIG. 3 is a top view thereof;
FIG. 4 is an enlarged top view thereof;
FIG. 5 is a bottom view thereof;
FIG. 6 is an enlarged bottom view thereof;
FIG. 7 is a left side view thereof;
FIG. 8 is a right side view thereof; and,
FIG. 9 is a perspective view thereof.
